Primary Examiner — Garth Rademaker*Assistant Examiner* — Richard Kearney(74) *Attorney, Agent, or Firm* — Davis & Bujold PLLC;
Michael J. Bujold(57) **CLAIM**

I claim the ornamental design for a ring, as shown and described.

DESCRIPTION

FIG. 1 is a front, top, left side perspective view of a ring in an exploded position;

FIG. 2 is a right side elevational view of the ring, the left, the top and the bottom views all being identical to FIG. 2; and,

FIG. 3 is a cross sectional view taken along section line 3-3 of FIG. 2.

1 Claim, 2 Drawing Sheets(56)
